UNITED STATES PATENT OFFICE.

ROYAL P. KNAPP, OF SAN FRANCISCO, CALIFORNIA, ASSIGNOR TO WILLIAM W. WALLACE, OF SAN FRANCISCO, CALIFORNIA.

DESIGN FOR A FINGER RING.

Application filed December 29, 1924. Serial No. 11,817. Term of patent 3½ years.

To all whom it may concern:

Be it known that I, ROYAL P. KNAPP, a citizen of the United States, residing at 1011 Bush Street, in the city and county of San Francisco and State of California, have invented a new, original, and ornamental Design for Finger Rings, of which the following is a specification, reference being had to the accompanying drawing, forming part thereof.

Fig. 1 is a side elevation, Fig. 2 is a top plan and Fig. 3 is an edge elevation of a finger ring, showing my new design.

I claim:

The ornamental design for a finger ring, as shown.

ROYAL P. KNAPP.
